UNITED STATES PATENT OFFICE.

THOMAS B. MACKEY, OF DALLAS, TEXAS.

RUNNING-GEAR FOR WAGONS.

SPECIFICATION forming part of Letters Patent No. 271,487, dated January 30, 1883.

Application filed October 9, 1882. (No model.)

To all whom it may concern:

Be it known that I, THOMAS BELL MACKEY, a citizen of the United States, and a resident of Dallas, in the county of Dallas and State of Texas, have invented a new and valuable Improvement in Wagons; and I do hereby declare that the following is a full, clear, and exact description of the construction and operation of the same, reference being had to the annexed drawings, making a part of this specification, and to the letters and figures of reference marked thereon.

Figure 1 of the drawings is a bottom view of my device. Fig. 2 is a rear view of the same. 15 Figs. 3, 4, and 5 are detail views.

The features constituting my invention are fully set forth in the following description and specifically pointed out in the claims.

Let A indicate the bolster of the rear section of the wagon; and B, the hounds, secured to the bolster and to the reach C.

D D are metal disks rigidly secured to the under side of the bolster and the hounds, and D' D' are rotary metal disks arranged to rotate upon the bolts d, which pass through the disks D, and serve to connect the hounds with the bolster.

E indicates rotary metal disks arranged upon the bolts between the two pairs of disks, 30 and provided with radial arms e, upon which are arranged the anti-friction rollers E'. These rollers travel in concave grooves formed in the opposing faces of the disks, and admit of the rotation of the lower disks with but little 35 friction.

The axle F is provided with a collar or wheel, f, under each pair of disks, the said collars bearing on the rotary disks, and thereby causing them to revolve when the axle is turned.

Within boxes G, which are secured to the bolster, are arranged anti-friction rollers g, against which the axle impinges, and below the boxes and the axle are arranged metal bands H, secured to the bolster and the boxes.

Within each box, above the axle, is arranged a horizontal anti-friction wheel, I. The collars f on the axle bear against these wheels, which prevent the axle from shifting endwise and avoid friction.

50 K K are diagonal braces secured to the rear ends of the hounds and the rear sides of the boxes, and K' are brace rods or straps secured

to the rear ends of the hounds and carried forward to the cross-bar L, to which they are fastened. The lower ends of the bolts on which the rotary disks turn are fixed in these braces K', and said braces are strengthened by the transverse rods l, secured both to the braces and to the bolster.

Inclined braces l' are also secured to the bolster and to the bands which pass around the boxes, as a further means of strengthening the structure.

The reach is set in a mortise in the bolster, and a metal plate, M, secured to the bolster, 65 so as to cross the reach. The hounds are secured to the reach by metal plates m, and a bolt, m', passed through the plates, the hounds, and the reach.

The front section of the wagon is provided 70 with the same arrangement of disks and anti-friction rollers as the rear section, and hence these need not be described in detail, but are simply lettered the same as those in the rear section. In the front section the bolts on 75 which the rotary disks are mounted are fixed at their lower ends in brace-bars m², secured at their forward ends to the cross-bar N. This bar is secured to the under side of the hounds, and is strengthened in its position by means 80 of the horizontal braces secured to its ends and to the boxes. In this section of the wagon the bands which are secured to the under side of the boxes also pass around the said cross-bar N, and are secured to the bolster, as shown. 85

O indicates a bent plate secured to the under side of the front bolster, so as to constitute a seat for the forward end of the reach, which passes between said plate and the bolster, and is held in connection therewith by means of a 90 bolt or pin, n.

P indicates a rocking bolster secured upon the lower bar or bolster of the front section of the wagon by the pin n passing through a slot in the rocking bolster.

95 Q indicates the pole, secured by a bolt between the ends of the front set of hounds, and R the double-tree.

The longitudinal spring S and the two diverging springs S', connected with the double-tree, serve to equalize the draft.

From the foregoing it will be seen that my wagon is strong and durable.

A stationary and a rotary disk, with anti-

friction rollers mounted on arms interposed between said disks, is not new in this connection, and is not broadly claimed herein; and friction-balls and vertical friction-rollers in boxes have been used for a single wheel and axle prior to my invention. I do not therefore broadly claim these devices herein.

Having thus described my invention, what I claim is—

- 15. 1. In a running-gear for carriages and wagons, the combination, with the axle provided with the collars *f*, of the stationary and rotary disks *D* and *D'*, and interposed anti-friction rollers *e*, mounted on arms projecting from disks *E*, which are mounted on bolts *d*, consti-

tuting axles for the rotary disks *E* and *D'*, and the horizontal wheels *I* and *g* in the boxes *G* substantially as specified.

2. The combination, with the boxes of the front section of the running-gear, of the bands secured to and passing around the boxes and the front cross-bar, substantially as described.

In testimony that I claim the above I have hereunto subscribed my name in the presence of two witnesses.

THOMAS BELL MACKEY.
